UNITED STATES PATENT OFFICE.

RUDOLF REITER AND RUDOLF LORENZ, OF LEIPZIG, GERMANY.

DEVICE FOR SECURING DOUBLY-BENT HOOKS.

1,130,105.

Specification of Letters Patent.

Patented Mar. 2, 1915.

Application filed May 28, 1914. Serial No. 841,435.

To all whom it may concern:

Be it known that we, RUDOLF REITER and RUDOLF LORENZ, both subjects of Germany, and residents of Leipzig, Saxony, Germany, have invented certain new and useful Improvements in Devices for Securing Doubly-Bent Hooks, of which the following is a specification.

This invention has reference to a novel device for securing doubly bent hooks or clasps to labels, tickets and various other objects.

Labels and tickets of cardboard, pasteboard and the like to be attached to paper boxes and other objects are usually provided with doubly bent securing hooks the free shanks of which protrude beyond the label or ticket for the purpose of having means to secure the labels or tickets to any object desired. The application of the securing hook or clasp to the label or ticket is effected by bending over the head portion of such hook or clasp immediately after the shanks have been pressed through the same. If this operation is to be done effectively then the head of the securing clasp must be seized in an exact way otherwise the clasp may be deformed.

In order to attain this desirable result we have produced a novel device for bending the head of the securing hook in the desired manner. This device comprises means having three protruding extensions adapted to engage and bend over the head of the hook, said means being guided between a spring actuated bolt and a rigid arm which is adjustably mounted.

The invention is illustrated in the accompanying drawing in which:

Figure 1 represents the device in side elevation. Fig. 2 illustrates the same in top plan view. Fig. 3 shows a bifurcated securing hook or clasp. Fig. 4 shows the bent hook in side elevation. Fig. 5 is a perspective view of the same.

Similar characters of reference denote like parts in all the figures.

Figs. 1 and 2 of the drawing represent the lower part of the machine only which contains the device for securing the hook to the label, ticket or the like. The cardboard label A is introduced sidewise into the device and placed upon the table B below the guiding plate C. The doubly bent securing hook is then forced through the cardboard label by means of the machine. For the

purpose of pressing the head D of the securing hook against the surface of the cardboard label, a member E is provided within the device. This member is mounted in the lower part F of the device. It extends upwardly in a slanting direction and is longitudinally movable. The member E may be shifted forward and backward by means of a two armed lever G. This lever actuates the member E by means of a link H which connects said lever and member. In addition to this forward and backward motion the member E is adapted to perform a slight motion in a vertical plane because its lower contact surface is rounded off, as shown in Fig. 1. The member E is guided between a spring actuated bolt I and a rigid but adjustably mounted guiding arm K. The bolt I rests upon the lower end portion of a pivoted arm L to the upper end of which a helical spring M is attached with one end, while the other end of said spring is secured to the table or machine frame. The guiding arm K is movable on the pivot K¹ and has on the top portion a nose adapted to engage an adjoining reduced portion of the member E. The bottom end of the arm K has a rectangular downward extension on which a set screw N acts for the purpose of adjusting said rigid arm K. For pressing the head D of the securing hook upon the surface of the cardboard label the top portion O of the member E is provided with three short extensions Q. The spaces formed between the three extensions Q are adapted to receive the shanks P of the hook whereby they are safely guided during the operation of pressing on the head D of the hook. The adjoining end portions of the extensions Q are beveled off so as to widen the spaces between them. Should the shanks enter these spaces in a slanting direction then the same are guided by the enlarged space sections and the wire shanks of the hooks are thereby properly directed and kept in a straight position. During the period of bending the head of the hook the three short extensions on the top O of the member E enter in corresponding recesses R of a counter support S for the hook. It is important that the member E seizes the head of the hook at the proper place, therefore, the height of the top O of the member E must be made adjustable. This is effected by the guiding arm K and the spring actuated bolt I which permit of

a slight displacement of the member E during its operation.

When the hook is forced through the cardboard label its shanks are liable to enter the recesses R of the counter support S. To prevent this spring actuated covers T are provided behind the entry openings of the recesses R. These covers when in their final position close said entry openings. The covers are located within the recesses and longitudinally movable therein under the action of helical springs U. It is sufficient if the outer openings are provided with such closing devices but all three recesses may have them so that they all may be periodically closed, while the long shanks of the hook D pass through the cardboard. The shanks then abut against cross strips of the counter support so that they enter the spaces between the short extensions on the top O of the member E when said member performs its forward movement. The extensions then press the covers T back overcoming the actions of the spring U and allow said extensions to enter the recesses R. In this manner the shanks of the hook are perfectly guided during the operation of pressing the head against the cardboard.

30 We claim as our invention:

1. A device for securing doubly bent hooks to flat objects comprising means for supporting the object and hook therein, a movable member having three short extensions on its front portion adapted to press on the head of the hook and to house the shanks of the hook during the bending of the head.

2. A device for securing doubly bent hooks to cardboard labels, tickets and the like comprising means for supporting the label and hook therein, a movable member having three short extensions with beveled off adjoining front portions to create widened spaces between them adapted to press the head of the hook onto the label and to guide and house the shanks of the hook during the bending of the head.

3. A device for securing doubly bent hooks to cardboard labels and the like comprising means for supporting the label with hook therein, a slantingly mounted movable member having three short extensions on its front top portion adapted to press on the head of the hook and to house its shanks during the bending of the head, a spring pressed bolt for guiding the lower surface of the bending member, and a pivotally ar-

ranged rigid arm for guiding its top surface.

60

4. A device for securing doubly bent hooks to cardboard labels and the like comprising a slantingly mounted movable member with three short extensions on its top front portion adapted to press on the head of the hook and to house its shanks during the bending of the head, supporting means for the label with hook therein having recesses adapted to receive the short extensions of the movable bending member during the bending of the head, and means for guiding said bending member.

65

5. A device for securing doubly bent hooks to cardboard labels and the like comprising a slantingly mounted movable member with three short extensions on its top front portion adapted to press on the head of the hook and to house its shanks during the bending of the head, supporting means for the label with hook therein having recesses adapted to receive the short extensions of the movable bending member during the bending of the head, spring actuated covers within said recesses adapted to periodically close their openings and to be forced in by the extensions of the bending member, and means for guiding said bending member.

75

6. In a device for securing doubly bent hooks to flat objects, supporting means for such objects with hook therein, a slantingly mounted movable bending member having three short extensions on its top front portion, and a slightly rounded bottom surface, and means for guiding said bending member during its forward and backward movement and permitting of a slight movement in a vertical plane.

80

7. In a device for securing doubly bent hooks to flat objects, supporting means for such objects with hook therein, a slantingly mounted movable bending member having three short extensions on its top front portion, and a slightly rounded bottom surface, a spring pressed lower guiding means for said bending member, and an adjustable top guiding member for the same permitting also of a slight movement of said bending member in a vertical plane.
